D. R. CAMPBELL,
BRANDING MACHINE,
APPLICATION FILED JUNE 23, 1916.

1,300,342.

Patented Apr. 15, 1919.

UNITED STATES PATENT OFFICE.

DUNCAN R. CAMPBELL, OF BOSTON, MASSACHUSETTS, ASSIGNOR, BY MESNE ASSIGNMENTS, TO ROBERT A. LINDEN, OF FLUSHING, NEW YORK.

BRANDING-MACHINE.

1,300,342.

Specification of Letters Patent. Patented Apr. 15, 1919.

Application filed June 23, 1916. Serial No. 105,517.

To all whom it may concern:

Be it known that I, DUNCAN R. CAMPBELL, a subject of the Dominion of Canada, residing at Boston, in the county of Suffolk 5 and State of Massachusetts, have invented new and useful Improvements in Branding-Machines, of which the following is a specification.

This invention relates to a machine for branding pieces of work, such as the sweat bands of hats, to indicate the ownership of the article by branding the initials of the owner on the sweat band, the machine including a carrier adapted to be reciprocated 10 by an operator, and in the preferred form of the machine, a disk movable with the carrier and adapted to be rotated theron, said disk having branding dies on its periphery, and heating means on the carrier 15 adapted to heat said branding dies so that when the carrier and disk are depressed against the work to be branded, a branding die brought by the rotation of the disk into operative position will act on the work.

20 The invention has for its object to provide a simple, conveniently operated and effective machine for the general purpose indicated, and is embodied in the improvements which I will now proceed to describe 25 and claim.

Of the accompanying drawings forming a part of this specification:

Figure 1 represents a front elevation of a branding machine embodying my invention;

35 Fig. 2 represents a section on line 2—2 of Fig. 1;

Fig. 3 represents a rear elevation of the branding disk;

Fig. 4 represents an edge view of the 40 same;

Fig. 5 represents a side view of a portion of the machine looking toward the side opposite that shown by Fig. 2;

Fig. 6 represents a view similar to a portion of Fig. 1, parts being shown in section.

The same reference characters indicate the same or similar parts in all the views.

In Figs. 1 to 6 of the drawings, 12 represents a supporting frame adapted to be attached to a bench or table and provided with an upper guide 13 and a lower guide 14, said guides being preferably in alinement with each other, and spaced apart, as indicated by Fig. 2.

Mounted to reciprocate in the space be-

tween the said guides is a carrier, which, in the preferred embodiment of the invention here shown, comprises a body portion 15, an upper extension 16, a lower extension 17, and an outwardly projecting arm 18 between said extensions.

The upper extension is preferably provided with teeth 19 constituting a rack, and the frame is provided with a rock-shaft 20 having gear teeth 21, constituting a pinion segment meshing with said rack. The shaft 20 may be rocked to alternately raise and depress the carrier by means of a hand lever 22. A spring 23 in the lower guide 14 normally presses the carrier upwardly, as indicated by Fig. 2. To the lower guide is fixed 65 an impression bed 24, preferably provided with a facing 25 of yielding or compressible material.

70 26 represents a disk of metal mounted to rotate on a bearing stud 27 forming a detachable part of the carrier and having a head 28 which confines the disk on the stud and permits the free rotation of the disk, said 75 stud being at right angles with the path of movement of the carrier.

The carrier is provided with an outwardly projecting flange 29 surrounding the stud 27 and arranged in a plane at right angles therewith. The disk 26 is provided with 80 an annular recess 30, opening toward the flange 29 and separated from the periphery of the disk by a relatively thin heat-conducting flange 31.

85 The carrier is provided with heating 90 means projecting into the recess 30 and preferably embodied in an annular electrical heating unit 32 attached, as indicated by Fig. 2, to the flange 29. The outer periphery of the heating unit is in close proximity to the inner side of the heat-conducting flange 31 and slightly spaced therefrom.

95 The periphery of the disk 26 is provided with branding dies 33, preferably formed on a ring or band 34 surrounding the periphery of the disk, and attached thereto by suitable means, such as screws 35. Heat is radiated by the heating unit against the heat-conducting flange 31 and conducted by 100 the latter to the branding dies, which are 105 therefore simultaneously heated.

To prevent or minimize loss of heat by radiation from the branding dies, I provide an outer rim 36 attached to the carrier flange 29 and overhanging the periphery of 110

the disk, said rim having an inwardly projecting annular flange 37 overlapping the marginal portion of the outer side of the disk. The rim 36, its flange 37 and carrier flange 39 constitute a heat-retaining hood or casing, which practically incloses the marginal portion of the disk and the branding dies thereon.

The lower portions of the carrier flange

29, the rim 36 and its flange 37 are truncated as shown at 40 (Fig. 1) to expose the branding dies 33 at the lower portion of the disk, said portion being so related to the impression bed 24 that when the carrier and 15 disk are depressed the lowest die on the disk will brand a sweat band *s* placed on the impression bed, said band being attached to a hat *h* and temporarily turned outwardly therefrom.

20 To the outer side of the disk is attached a spider composed of an annular marginal portion 42, a hub portion 43, radial arms 44 connecting the portions 42 and 43, said arms being separated by air spaces so that the 25 spider is air-cooled.

45 represents a disk-rotating knob or handle, preferably of wood or other material which is a non-conductor of heat. Said handle is in alignment with the stud 30 27 and coaxial with the disk, and is secured to the spider hub 43 by means of a bolt 47 engaged with the spider hub and having a knob-confining nut 48 engaged with the knob, as indicated by Figs. 1 and 2.

35 The operator by rotating the handle 45 is enabled to bring any desired branding die into operative position, suitable means being provided for yieldingly confining the disk with any die in position to operate, 40 said means being preferably embodied in a spring-pressed detent 50 (Fig. 2) adapted to engage either of a series of sockets 53 formed in the inner edge of the disk flange 31 and corresponding in number and 45 position to the branding dies, as indicated by Fig. 3.

The hood flange 37 is provided with an indicating member 54 arranged to coöperate with either of a circular series of indicating members 55 on the annular marginal portion 42 of the spider, said indicating members informing the operator which branding die is in operative position.

It will be seen that the described machine 55 is adapted to conveniently brand hat sweat bands and other like articles.

To enable the impressions made by the branding dies to be uniformly spaced apart, I provide the means next described.

60 To a suitable portion of the frame at one edge of the impression bed I secure by a screw or screws 57 (Fig. 5) a pair of spring jaws 58, between which a sweat band *s* may be yieldingly grasped, the object of said 65 jaws being to prevent loose movement of the

sweat band and permit it to be moved by the application of suitable force.

In the impression bed is a cavity 59 (Fig. 6), in which a slide 60 is movable by the operator, said slide being normally held in 70 the position shown by Fig. 6 by a spring 61 in said cavity.

The slide has a reduced portion 62 projecting from one side of the impression bed and adapted to be grasped and moved by 75 the operator.

A portion of the outwardly turned sweat band projects over the extension 62, and said portion and extension may be grasped between the operator's thumb and forefinger 80 and moved in the direction of the arrow (Fig. 1) after a character has been impressed on the band. This movement, continued until the slide 60 is arrested by the compressed spring 61, shifts the sweat band 85 to position to receive another impression at a predetermined distance from the first. When the branding is completed the sweat band may be withdrawn edgewise from the jaws 58. When the slide is released it is 90 retracted by the spring 61 until arrested by the bearing of a stop shoulder 63 thereon against one side of the impression bed.

Having described my invention, I claim:

1. A branding machine comprising a carrier, a supporting frame having carrier-guiding and carrier-reciprocating means, said carrier including a bearing stud and a flange surrounding said stud, a disk rotatable on said stud and provided with branding dies on its periphery and with an annular recess opening toward said flange and separated from the periphery of the disk by a relatively thin heat-conducting rim, and heating means supported by said flange 105 and projecting into said recess in close proximity to the inner surface of said heat-conducting rim.

2. A branding machine comprising a carrier, a supporting frame having carrier-guiding and carrier-reciprocating means, said carrier including a bearing stud and a flange surrounding said stud, a disk rotatable on said stud and provided with branding dies on its periphery and with an annular recess opening toward said flange and separated from the periphery of the disk by a relatively thin heat-conducting rim, and an annular electrical heating unit attached to said flange and projecting into said recess, the outer periphery of said unit being in close proximity to and slightly spaced from the inner surface of said heat-conducting rim.

3. A branding machine comprising a carrier, a supporting frame having carrier-guiding and carrier-reciprocating means, said carrier including a bearing stud and a flange surrounding said stud, a disk rotatable on said stud and provided with branding dies 125

- on its periphery and with an annular recess opening toward said flange and separated from the periphery of the disk by a relatively thin heat-conducting rim, heating means supported by said flange and projecting into said recess in close proximity to the inner surface of said heat-conducting rim, and a circular flanged rim attached to said flange and forming therewith a heat-confining chamber surrounding the greater portion of the periphery of the disk, the lower portion of said flange and rim being truncated to expose the lower portion of the periphery of the disk.
- 5 4. A branding machine comprising a supporting frame having carrier-guiding and reciprocating means, a carrier guided and reciprocated by said means and including a bearing stud arranged at right angles to the path of movement of the carrier, a rotatable disk journaled on said stud and provided with branding dies on its periphery, and with an air-cooled spider attached to the outer side of the disk and bridging said
- 10 20 25 30 35 40 45 50 55 60
- stud, a disk-rotating handle attached to said spider and coaxial with the disk, and heating means supported by the carrier and operatively related to said dies to simultaneously heat the same.
5. A branding machine comprising a carrier, a supporting frame having carrier-
- guiding and carrier-reciprocating means, said carrier including a body portion having a circular outwardly facing flange and an outwardly projecting bearing stud surrounded by said flange, a disk rotatable on said stud and provided with branding dies on its periphery and with an annular recess opening toward said flange and separated from the periphery of the disk by a relatively thin heat-conducting rim, heating means on said flange projecting into said recess, a fixed rim attached to the flange and overhanging the main portion of the periphery of the disk, said rim having an inwardly projecting annular flange overlapping the marginal portion of the outer side of the disk, said fixed rim and its flange and the carrier flange forming a heat-retaining casing, which is truncated at its lower portion to expose the lower portion of the disk, a spider attached to the outer side of the disk and bridging said stud, and a disk-rotating handle attached to said spider, the casing flange being provided with a fixed indicating member, and the spider with a circular series of indicating members corresponding to the branding dies and co-operating with said fixed member.

In testimony whereof I have affixed my signature.

DUNCAN R. CAMPBELL.
